Patented July 18, 1916.

UNITED STATES PATENT OFFICE.

ADOLPH E. POLLOCK, OF NEW YORK, N. Y., ASSIGNOR TO IMPROVED STAY COMPANY, A CORPORATION OF NEW JERSEY.

CORSET-FASTENER.

1,191,910.

Specification of Letters Patent. Patented July 18, 1916.

Application filed April 3, 1915. Serial No. 18,905.

To all whom it may concern:

Be it known that I, ADOLPH E. POLLOCK, a citizen of the United States, residing in the city of New York, county of Bronx, and 5 State of New York, have invented a certain new and useful Corset-Fastener, of which the following is a specification.

This invention is a corset fastener, the same being intended, more particularly, as 10 an improvement upon the device disclosed in a prior Patent No. 1,075,438 granted to Rosenberg and myself on October 14, 1913.

In my present invention the device is constructed to meet the demand for a compact, 15 simple and economical construction of a flexible character and of small cross sectional dimensions so that for all practical purposes the new fastener will serve as a corset steel. At the same time the device embodies means 20 whereby the studs may be individually connected to the keepers and retained separately by the latches, provision being made for the simultaneous release of said latches in order that the fastening may be quickly uncoupled 25 to the end that the corset may be removed with ease and facility.

An important feature of my device consists in the provision of latches which are positioned for the hooks thereof to point 30 downwardly, in order that the studs cannot be pulled out of position or disengaged from the latches during the operation of fitting said studs successively into engagement with the keepers and the latches.

35 Another feature is a compact flexible construction of the steel composed of two connected flat pieces with an intermediate releasing bar, the latter coöperating with all the latches in such a way as to permit individual pivotal movement of said latches and at the same time said bar will act simultaneously on the latches for releasing the studs.

Another feature consists in the combination with a series of keepers on a metal member of a series of pivoted latches each having a spring, and a single releasing bar in contact with said latches, said springs acting on the latches for individually retaining the same in position and certain or all of 50 said springs and latches controlling the position of the releasing bar for retaining the latter in an at rest position, whereby a separate spring for the releasing bar is obviated.

Other features and advantages of the invention will appear from the following detailed description.

In the drawings, Figure 1 is an elevation of a corset fastener embodying my invention. Fig. 2 is an elevation of the latch carrying member with one of the plates removed to show the latches and the release bar. Fig. 3 is an enlarged cross section on the line 3—3 of Fig. 2. Fig. 4 is an enlarged cross section through the keeper on the line 4—4 of Fig. 2. Fig. 5 is a detail view of one of the latches. Fig. 6 is a detail cross section on the line 6—6 of Fig. 3 to show the ribbed form of the keeper whereby the keeper is stiffened so as to preclude bending. Fig. 7 is a detail view in 70 elevation, partly in section, illustrating a preferred form of the latch and the means whereby the latch is retained in position, thus facilitating assemblage of the latch with respect to the keeper and the other 75 parts of the device.

The flexible latch-carrying member of my fastener comprises a pair of parallel yieldable plates 10, 11, composed of thin metal, each stamped from a single piece of sheet 80 material. The plate 10 is provided with rows of spacing studs 12 positioned in contact with plate 11 for retaining said plates in spaced parallel relation. One of said plates is provided at the respective edges 85 with clips 13 adapted to embrace the other plate so as to retain the two plates in a connected condition, although it may be desired to permit one plate to slide endwise relatively to the other plate. The plate 10 is 90 provided, also, with a series of integral keepers 14, each struck up with plate 10 from a single piece of metal. The keepers are spaced on the plate 10 and project from one edge thereof, each keeper being folded 95 or doubled upon itself and the free end of the metal being formed with a stud 15 which enters an aperture in the other part of the keeper or in the plate 10. Each keeper is provided in the two parts of the 100 folded metal composing it with a slot 16, the end 16^a of which opens or extends through the free end part of said keeper.

A series of latches 17 are employed, the number of latches corresponding to the 105 keepers, and each latch and the actuating spring therefor being composed of a single piece of metal, preferably a single stamping. The latch is provided with a curved heel 18, a hook 19, a spring 20 and a guide slot 21, 110 said spring being integral with the latch and extending outwardly from the pivotal

2
end thereof. Said latches are positioned so as to be partially incased by and between the parallel plates and for the hooks to lie within the doubled keepers, each latch being pivoted as, e. g., by a stud or tubular rivet 22 of the plate 10 fitting in an aperture provided in the heel of the latch. The springs 20 of said latches are in contact with other studs or tubular rivets 23 on the plate 10, 10 said tubular rivets 22, 23 being punched up from the metal of the plate 10. The guide slot 21 of the latch is concentric with the pivot 22, said slot receiving the stud 15 of the keeper with which the latch coöperates, 15 whereby the latch is retained in proper position by the coöperating plates 10, 11, and the doubled keeper.

24 designates a releasing bar which is incased by the plates 10, 11 and is slidably retained in position therebetween by one row of clips 13 and one row of spacing studs 12. The bar 24 is a single stamping of flexible metal so as to flex with the plates 10, 11 of the latch-carrying member; said bar being provided with a series of spaced fingers 25 which extend from the bar and are curved lengthwise, each finger being a rounded end 26 in contact with the curved heel 18 of one latch, as shown. The bar 24 is provided 30 near one end with a shoulder 27 which engages a finger 28 of an operating finger piece 29, the latter being composed of a flat plate and stamped from a single piece of metal. The member 29 is pivoted between the plates by a tubular stud 30, and said member is provided with a curved guide slot 31 in which fits a tubular stud 32 stamped up from the plate 10. The finger piece of the operating member extends outside of the plates 10, 11, so as to be exposed 35 for convenient access in order to apply pressure in a manner to impart movement in one direction to the release bar. A second member 33 is provided with the usual studs 34 adapted to enter the slotted keepers of the flexible member to be engaged and retained by the latches. The two members, one provided with studs, and the other with the keepers and the latches, are adapted to 40 be secured as usual to the two edges of the corset or other device to be coupled. In my fastener, the studs of one member are intended to be engaged separately and successively with the keepers on the other member, for which purpose the latches are yieldable individually with respect to the release bar, and during this coupling operation the studs engaged with one keeper are precluded from pulling out of engagement 45 with the latches for the reason that the hooks of said latches are pointed downwardly so that the studs can be rotated relatively to and in contact with said hooks of the latches during the coupling operation. 50 As the stud passes through the open end of

the slotted keeper, said stud rides against the beveled edge of the hook shaped latch, whereby the latter turns on its pivot against the resistance of the spring, said latch rising or lifting away from the curved end 70 of the finger on the release bar so that the latches are movable independently of said bar. After the stud clears the hook of the latch, the spring forces the latch back into position for again closing the throat to the 75 slot in the keeper, thus precluding the stud from releasing itself or passing out of the slotted keeper. To release the latches simultaneously it is only necessary to press upon the finger piece, whereupon the release bar 80 is lifted and all the fingers of said release bar exert pressure upon the curved heels of the latches, the latter being turned simultaneously on their individual pivots and against the tension of their separate springs 85 so as to retract the latches relatively to the keepers and thus open the slots in said keepers for the free egress of all the studs at one operation. The fastener thus permits the studs to be disengaged from the keepers at 90 one operation, and the corset can thus be released and removed with ease and facility.

It will be noted that in my device the release bar is not controlled by or associated with a spring separate from the springs of 95 the individual latches, but, on the contrary, the latch springs perform the double function of retaining the latches individually in their normal closed positions and of retaining the release bar in a normal position in 100 contact with all the latches, while at the same time the parts are so organized and related that the latches are free to move in a direction necessary for the stud to enter the keeper without affecting or changing the 105 position of the release bar.

A characteristic feature of my invention is the flexible member carrying the keepers and latches, said member being so compact in construction that its cross sectional dimension is practically the same as an ordinary corset steel.

It is found in practice that the keeper 14 is liable to bend out of position under the strain of the stud 34 or from other causes. 115 In order to stiffen the keeper to such an extent as to preclude bending, I prefer to provide the ribs or corrugations 35, see Figs. 3 and 6, said ribs being formed in the metal of the keeper on opposite sides of the slot 120 16 and said ribs extending into the metal of the plate 10 to a point beyond the edge of the plate. This construction adds materially to the strength of the keeper, particularly when it is made integral with the 125 plate 10, and it so stiffens the keeper as to prevent bending under ordinary conditions of use.

When assembling the slotted latch 17, with the keeper 14 it is necessary to first 130

position the latch within the keeper and then to insert the stud 15 through the slot 21, the upper part of the keeper being bent to thus insert the stud and said stud being 5 thereafter bent against the plate 10. To facilitate assemblage, it is preferred to construct the latch and the keeper as in Fig. 7, whereby the slot 21 is omitted in the latch and the keeper is formed with two studs 36, 10 one of which co-operates with a recess 37 in the latch, so as to limit the movement of the latch relative to the keeper. In the preferred form shown, the upper member of the keeper is provided with two studs 36 15 which are inserted through the plate 10 and clenched at the time of bending up the metal. The latch is formed with the recess 37, and said latch is inserted into the keeper between the studs 36, the latch being slipped 20 over the pivot stud 22 and the spring fitted against the stud 23, whereby the assemblage of the latches is facilitated.

In my device the latches and the release bar are positioned and retained between the plates 10, 11, and in practice it is found that when the stay is bent or curved there is a 25 relative movement between the plates due to the arcuate form assumed by them, and, accordingly, the frictional contact of the 30 latches with one plate may and sometimes does result in movement of the latch or latches so as to release the studs. To overcome this defect, the latches and the fingers of the release bar are so positioned and arranged as to secure a limited lost motion 35 between them. This enables the two plates, the release bar and the latches to bend in one direction or the other without affecting the position of the latches relative to the 40 keepers. Thus in the drawings the latches 17 and fingers 25 of the release bar are not in actual contact, but a slight interval or space is left between the edges of the latches and the fingers of the release bar.

45 Having thus fully described the invention, what I claim as new, and desire to secure by Letters Patent is:

1. In a fastener, the combination with a 50 stay having studs, a second stay, and slotted keepers on said second stay, of latches pivoted to the second stay for co-operation with said keepers and adapted to retain the studs of the first stay within the slots of said keepers, and a releasing bar for imparting movement to said latches, said releasing bar being free from direct attachment to said latches and co-operating therewith to secure a limited lost motion whereby the second stay is free to flex or bend 55 and the latches are adapted to conform thereto without being acted upon by said releasing bar to free the studs from the keepers or from the latches.

60 2. In a fastener, the combination with a stay having studs, a flexible second stay,

and keepers on said second stay, of latches free from direct attachment to the keepers and pivoted to the second stay, whereby the latches are adapted to conform to the bending or flexing movements of the second stay 70 while operating to retain the studs within the keepers, and a releasing bar free from direct attachment to said latches to secure a limited lost motion between said bar and the latches so as to retain the releasing bar 75 in operative relation to said latches.

3. In a fastener, the combination with a flexible stay and keepers provided with slots which extend through the ends thereof distant from the stay, of latches each pivoted to 80 said stay and free from attachment to the keeper with which the latch is associated, means for retaining each latch in a position to close the open end of the slot of said keeper with which the latch co-operates, and 85 a flexible releasing member slidable with respect to the stay, said releasing member having operating means free from direct attachment to the latches and adapted to operate said latches simultaneously by a movement in one direction of said releasing member.

4. In a fastener of the class described, a stay provided interiorly thereof with a substantially continuous chamber, and a plurality of chambered keepers positioned exteriorly to said stay, the chambers of said keepers being in substantial register with said chamber of the stay, combined with disconnected latches incased partially within 100 the chamber of the stay and each latch being incased partially within a chamber of one of said keepers, and releasing means incased by the stay and co-operating with the incased parts of said latches.

105 5. In a fastener, the combination of a flexible stay provided with a substantially closed latch-receiving space or chamber, a plurality of keepers each provided with a latch-receiving space or chamber and with a stud-receiving slot, a plurality of latches pivoted to the stay, said latches being substantially incased within the space of the stay and the space of the keepers, and a releasing member incased also by the stay and 110 co-operating with the latches.

6. In a corset fastener, a flexible member composed of a plurality of parallel yieldable plates connected together and provided with a series of keepers, combined with a 115 release bar slidable between said plates and incased thereby, and latches pivoted between said plates and co-operating with said keepers and with the release bar, said latches being substantially incased between said 120 plates and by the keepers.

125 7. In a corset fastener, a flexible member composed of a plurality of plates held apart by spacing studs and connected together by clips, one of said plates being provided 130

with keepers, combined with latches pivoted between the plates and movable with respect to the keepers, and a release bar slidably confined between the plates, said release bar being provided with fingers normally in contact with said latches.

8. A flexible stay embodying a plate and a plurality of keepers, each keeper being composed of a plate unitary with the stay 10 plate and folded upon itself to produce two parts, said parts of the keeper being provided with slots which open through the end of the keeper distant from the plate and said keeper being provided adjacent to the 15 slot therein with a rib for stiffening the parts against bending relatively to each other, combined with separate latches positioned for operation intermediate the parts of the keeper and across the slots therein, 20 said latches being individually pivoted to the stay and free from direct attachment to the keepers, and means for operating the latches.

9. In a fastener of the class described, a 25 stay plate, and a keeper, said keeper comprising two parts positioned parallel to each other and one of which is unitary with said stay plate, the other of said keeper parts being provided with prongs which are attached to the first named part, and said prongs being spaced relatively to each other whereby said prongs serve as stops in limiting the movement of a latch, combined 30 with a latch partially incased within the keeper and positioned for movement between said prongs, means for retaining the latch in operative relation to the plate and the keeper, and means for operating the latch.

10. In a corset stay, the combination of a 40 plate provided with a series of keepers, a series of spring-pressed latches pivoted to said plate, and a release bar free from direct spring control, said release bar being provided with fingers positioned in such relation 45 to the latches that a limited lost motion is secured between the bar and the latches whereby the stay and the bar are free to flex without affecting the latches.

11. In a fastener of the class described, a 50 flexible stay composed of a plurality of plates positioned in parallel relation to each other and fastened together, said plates of the stay being relatively spaced to produce a substantially continuous chamber, and a 55 plurality of keepers rigid with one of said plates and positioned exteriorly to the stay, each keeper being provided with a slot and with a chamber, said chambers of the keepers being in substantial register with the chamber 60 of the stay, combined with disconnected latches each partially incased by the cham-

ber of the stay and by the chamber of one of the keepers, each latch being pivoted to the stay, and a releasing member incased within the stay, said releasing member co-operating with the parts of the latches incased within the stay. 65

12. In a fastener, a chambered stay provided with a plurality of chambered keepers, said keepers projecting from the 70 edge of the chamber stay and each keeper being slotted for receiving studs on a companion stay, combined with latches substantially incased by said chambered stay and the chambered keepers, each latch being pivoted within the chambered stay, and a releasing member also substantially incased by the stay for co-operation with said latches. 75

13. In a fastener of the class described, a stay provided interiorly thereof with a space 80 extending substantially continuously within the same, and a plurality of keepers extending outwardly from an edge portion of the stay, each keeper being provided interiorly thereof with a space which is in substantial 85 register with said continuous space of the stay, combined with latches substantially incased within the spaces of the stay and the keepers, said latches being pivoted to the stay, means for retaining each latch normally in a closed position relatively to the keeper with which the latch is associated, and a releasing member incased by the stay, 90 said releasing member being free from direct attachment to said latches. 95

14. In a fastener, a stay provided with an interior space and with a plurality of keepers each having a space interiorly thereof, combined with latches substantially incased by the spaces of the stay and the keepers, 100 said latches being provided with an attached spring and each latch being pivoted to the stay for the spring to retain the latch in closed relation to one keeper, and releasing means for said latches. 105

15. In a fastener, a stay comprising separate plates providing a latch receiving space, and a series of keepers integral with one of said plates, each keeper being composed of metal folded to produce two parts one of 110 which is substantially flush with the other of said stay plates, combined with latches substantially incased between the plates of the stay, and within the two parts of the respective keepers, and means for actuating 115 said latches.

In testimony whereof I have signed my name to this specification.
